UNITED STATES PATENT OFFICE.

CHARLES BARRELLIER, OF PARIS, FRANCE.

HAND-PROPELLED VEHICLE.

1,308,270.

Specification of Letters Patent.

Patented July 1, 1919.

Application filed April 30, 1919. Serial No. 293,822.

To all whom it may concern:

Be it known that I, CHARLES BARRELLIER, citizen of the Republic of France, residing at 2 Rue Blanche, Paris, in the Republic of France, have invented new and useful Improvements in Hand-Propelled Vehicles, of which the following is a specification.

This invention relates to a hand propelled chair or carriage for wounded persons and invalids, which is entirely constructed of metal and of a very strong and light construction. Said vehicle has a very flexible suspension and it may be driven and steered very easily by the invalid acting by his hands.

In the annexed drawings given by way of example,

Figure 1 is a vertical longitudinal section of the vehicle, partly in elevation.

Fig. 2 is a plan view partly in section.

Fig. 3 is an end view from the rear.

The improved carriage comprises a frame C which is made entirely of metal tubing, and is carried at its front end on the steering fork p through the medium of the coiled spring d. V is the front steering wheel.

The frame C is extended upwardly at the rear so as to form the back C¹ of the seat. The two vertical posts a which support the seat at its front end are also made of metal tubes as well as the arms b of the seat.

The frame is supported at the rear by two pairs of springs. Each of said pairs is composed of two concentric coil springs c, c¹, the inner coil c¹ being less flexible than the outer one and so arranged that it comes into play only when the load or the displacement resulting from the shock exceed a certain limit. The springs c, c¹ are attached to the outer casings y of roller bearings in which the rear axle w is rotatably supported, the hubs u of the rear wheels being secured to said axle. The casings y are connected to the front posts a by two struts t pivotally connected to said front posts a. The axle w is driven through a connecting rod f which is connected to a crank formed in the middle of the length of the axle and is pivotally connected at its front end to the driving post or tube g.

The said tube g is secured at its lower end upon a transverse shaft h journaled at its ends in bearings provided on the side members C of the vehicle. By oscillating the tube g back and forth, the person sitting on the carriage may easily propel the same.

The vehicle is steered by means of a hand wheel 2 secured upon tube 5 which has a reduced portion extending downward through the tube g and shaft h and journaled in said tube g. Keyed upon the lower end of said tube 5, is a horizontal transverse lever arm 6, the free end of which is pivotally connected to a connecting rod j having its front end pivotally connected to a lateral arm 4 (Fig. 65 2) on the steering fork p.

The seat q of the carriage is made of a perforated metal-sheet and is supported at the front upon two springs m and at the rear upon two springs n.

A urinal box r made of sheet metal is carried on the side members of the frame beneath the seat. The foot board which is also carried by the side members of the frame is formed of a metal sheet.

Having now described my invention what I claim as new and desire to secure by Letters Patent is:

1. A hand propelled chair comprising in combination a frame, two rear propelling wheels, a front steering wheel, an axle upon which both propelling wheels are fixed, a crank formed on said axle, a connecting rod engaging with said crank, a hollow reciprocal driving member to which said connecting rod is connected, a rotary member freely mounted on the driving member, means extending through the driving member and connecting the rotary member to the steering wheel, bearings in which the rear axle is mounted, tension springs connecting the frame to said bearings, and pivotally mounted struts connecting the bearings to a part of the frame, remote from said bearings.

2. A hand propelled chair comprising in combination a frame formed of metal tubing, a seat carried on said frame, two rear propelling wheels, a front steering fork, a wheel journaled in said fork, an axle upon which both propelling wheels are fixed, a crank formed on said axle, a connecting rod engaging with said crank, a tubular lever to which said connecting rod is pivotally connected, a cross shaft secured to the lower end of said tubular lever, bearings on the frame in which said shaft is journaled, resilient means connecting the frame to the bearings, pivotally mounted struts connecting the bearings to the tubular members supporting the seat, a steering tube carried on the upper end of the tubular lever and ex-

tending through the latter, a lever arm secured on the lower end of said steering tube, a lateral arm provided on the steering fork and a connecting rod extending from the 5 lever arm to the lateral arm.

3. A hand propelled chair comprising in combination a frame composed of two tubular side members, tubular cross members and tubular members affording supporting means 10 for a seat, a seat on said supporting means, the rear end of the tubular side members being extended upwardly to form a back for the seat, two rear propelling wheels, a front steering fork, a wheel journaled in 15 said fork, an axle upon which both propelling wheels are fixed, a crank formed on said axle, a connecting rod engaging with said

crank, a hollow driving member to which said connecting rod is connected, means for supporting the hollow driving member so 20 that it may be swung back and forth, a rotary member freely mounted on the driving member, means extending through the driving member and connecting the rotary member to the steering fork, bearings in which 25 the rear axle is mounted, tension springs connecting the frame to the said bearings and pivotally mounted struts connecting the bearings to tubular members supporting the seat. 30

In testimony whereof I have signed my name to this specification.

CHARLES BARRELLIER.
